DEVICE FOR STACKING CASES OR
THE LIKE

Ralph P. Alexander, Slater, S. C.

Application January 8, 1944, Serial No. 517,614

8 Claims. (Cl. 193—42)

My invention relates to a device for use in stacking cases, file sections or the like.

An important object of the invention is to provide a device of the above mentioned character by means of which heavy cases or the like may be stacked and unstacked with the minimum effort.

A further object of the invention is to provide a device of the above mentioned character which may be applied to the lower case and will serve to guide and roll the next upper case into position, and which may be subsequently removed from between the superposed cases.

A further object of the invention is to provide a device of the above mentioned character which is adjustable for use with cases of different sizes.

A further object of the invention is to provide a device of the above mentioned character which is simple in construction and easy to operate.

Other objects and advantages of the invention will be apparent during the course of the following description.

In the accompanying drawing forming a part of this application and in which like numerals are employed to designate like parts throughout the same,

Figure 1 is a side elevation of a device embodying my invention, showing the same in use,

Figure 2 is a front end elevation of the same,

Figure 3 is a transverse section taken on line 3'—3' of Figure 1,

Figure 3' is a prospective view of the device removed, and,

Figure 4 is a side elevation of a modified form of the invention, parts broken away.

Figure 4' is a section taken on line 4'—4' of Figure 3.

In the drawing, wherein for the purpose of illustration is shown a preferred embodiment of my invention, the numeral 5 designates a preferably rectangular frame, which is longitudinally and transversely adjustable. This frame comprises sides, each of which includes side sections 6 and 7, arranged in contacting relation. The side section 6 is provided at its free end with a sleeve 8, slidably receiving the side section 7, while the side section 7 is provided at its free end with a sleeve 9, slidably receiving the side section 6. The sleeve 8 has an opening 10 to receive a pin 11, for insertion within selected openings 12. The frame further comprises ends, each of which includes end sections 14 and 15, arranged in contacting relation. The end section 14 is provided at its free end with a sleeve 16, slidably receiving the end section 15, and the end section

15 is provided at its free end with a sleeve 17, slidably receiving the end section 14. The sleeve 16 has a transverse opening 18, to receive a pin 19, for insertion within a selected opening 19, formed in the end section 15.

Preferably formed integral with the rear ends of the side sections 6 are U-shaped corner frames 20, also preferably formed integral with the rear end sections 14 and 15. Each U-shaped corner frame or bracket includes sides 21 and 22, having upstanding knuckles 23. These knuckles are provided with openings to receive a transverse horizontal shaft 24, carrying rollers 25 and 26, as shown. Each side 22 is provided at its rear end with a depending end stop 27, and is provided forwardly of and spaced from the end stop 27 with a side stop 28.

Preferably formed integral with the forward ends of the side sections 7 are forward U-shaped corner frames or brackets 29, also preferably formed integral with the end sections 14 and 15. Each U-shaped frame or bracket 29 includes sides 30, provided with upstanding knuckles 31, having openings to receive a horizontal transverse shaft 32, carrying rollers 33 and 34. The sides 30 have depending knuckles 35, having openings to receive a horizontal transverse shaft 36, carrying rollers 37 and 38. The rollers 37 and 38 extend below the knuckles 35, as shown.

The numeral 39 designates heavy cases or file sections to be stacked. Each case may be provided at its top with longitudinal and transverse cleats or strips 40 and 41, as shown.

The operation of the device is as follows:

The lowermost case 39 is placed in position and the device is arranged upon the top of the case, adjacent to its rear end. The rear corner frames or brackets 20 rest upon the longitudinal and transverse strips or cleats 40 and 41. The end stops 27 are disposed upon the rear outer side of the transverse strip 41 and serve to hold the device from moving forwardly with respect to the lower casing. The side stops 28 are disposed upon the inner or forward side of the transverse strip 41 and upon the inner sides of the longitudinal strips 40, and prevent the lateral displacement of the device with respect to the lower casing 39. The rollers 37 rest upon the longitudinal strips 40. With the device thus arranged, the next case 39 is elevated and its forward end placed upon the rollers 25, which support the same, and the upper case is then rolled forwardly until its forward end passes over the upper rollers 33. The forward movement of the case is continued until its forward

end is adjacent to the forward end of the lower case, at which time the forward end of the upper case may be lowered to rest upon the lower case, the parts then showing the position as indicated in Figure 1. The rear end of the device is now raised, to permit the side stops 28 to clear the transverse strip 41, after which the device is moved rearwardly, the upper rollers 33 engaging the upper case and the lower rollers 37 engaging the lower case. The rear end of the upper case is supported before the device is completely removed from beneath the same, after which the rear end of the upper case is lowered into engagement with the lower case, thus completing the stacking operation.

In Figure 4 I have shown a slight modification of the invention to be used with cases having flat tops without the longitudinal and transverse strips 40 and 41. The side stops 28 are omitted and the sides 21 and 22 of the rear corner frames or brackets are provided at their lower edges with teeth or serrations 42 to engage with the top of the lower case to hold the device against lateral displacement. All other parts of the device are identical with those shown and described in connection with the first form of the invention.

It is to be understood that the forms of my invention are to be taken as preferred examples of the same, and that various changes in the shape, size, and arrangement of parts may be resorted to, without departing from the spirit of the invention or the scope of the subjoined claims.

Having thus described my invention, what I claim is:

1. A device for stacking cases or the like having longitudinal and transverse strips at their tops, comprising a frame to be arranged upon the top of the lower case, end stops secured to the frame near its rear end and positioned upon the rear side of the adjacent transverse strip, side stops secured to the frame near its rear end and to be positioned upon the inner sides of the longitudinal strips, roller means mounted upon the frame near its rear end for supporting the next upper case, roller means mounted upon the frame near its forward end for supporting the next upper case, and roller means mounted upon the frame near its forward end to travel upon the lower case.

2. A device for stacking cases or the like having longitudinal and transverse strips at their tops, comprising a frame to be arranged upon the top of the lower case, means carried by the frame to engage the rear transverse strip to prevent the forward movement of the frame with respect to the lower case, means carried by the frame to engage the longitudinal strips to prevent the lateral movement of the frame with respect to the case, roller means mounted upon the frame near its rear end to support the next upper case, roller means mounted upon the frame near its forward end to support the next upper case, and roller means mounted upon the frame near its forward end to travel upon the lower case.

3. A device for stacking cases or the like, comprising a frame to be arranged upon the top of

the lower case, means to prevent the movement of the frame with relation to the lower case, said means including a device carried by the frame and arranged to engage the lower case, rear upper roller means mounted upon the frame to support the next upper case, forward upper roller means mounted upon the frame to support the next upper case, and forward lower roller means mounted upon the frame to travel upon the lower case.

4. A device for stacking cases or the like, comprising a substantially rectangular frame, means to adjust the frame longitudinally and transversely, a transverse pair of rear rollers mounted upon the frame adjacent to its rear corners for supporting the next upper case, a transverse pair of forward rollers mounted upon the frame adjacent to its forward corners for supporting the next upper case, and a transverse pair of rollers mounted upon the frame adjacent to its forward corners for traveling upon the lower case.

5. A device for stacking cases or the like, comprising a supporting unit to be arranged upon the top of the lower case, means carried by the supporting unit to engage the lower case to prevent the supporting unit from being shifted longitudinally with respect to the lower case, rear upper roller means mounted upon the supporting unit to support the next upper case, forward upper roller means mounted upon the supporting unit to support the next upper case, and forward lower roller means mounted upon the supporting unit to travel upon the lower case.

6. A device for stacking cases or the like, comprising a supporting unit to be arranged upon the top of the lower case, said supporting unit having serrations to engage the lower case to prevent the movement of the supporting unit with relation to the lower case, rear upper roller means mounted upon the supporting unit to support the next upper case, forward upper roller means mounted upon the supporting unit to support the next upper case, and forward lower roller means mounted upon the supporting unit to travel upon the lower case.

7. A device for stacking cases or the like, comprising a substantially rectangular frame, said frame comprising longitudinally adjustable sides and longitudinally adjustable ends and individual frames at the corners of the first-named frame, the individual frames being secured to the sides and the ends, a transverse pair of rear upper rollers mounted upon the rear individual frames, a transverse pair of forward upper rollers mounted upon the forward individual frames, and a transverse pair of lower forward rollers mounted upon the forward individual frames.

8. A device for stacking cases or the like, comprising a substantially rectangular frame, said frame comprising sides and ends and individual frames at the corners of the first named frame, a transverse pair of rear upper rollers mounted upon the rear individual frames, a transverse pair of forward upper rollers mounted upon the forward individual frames, and a transverse pair of lower forward rollers mounted upon the forward individual frames.

RALPH P. ALEXANDER.
